To all whom it may concern:

Be it known that I, GEORGE E. PICKUP, a citizen
of the United States, residing at Newark, in the
county of Licking and State of Ohio, have in-
vented a new, original, and ornamental Design
for a Solid Fuel Range, of which the following is
a specification, reference being had to the accom-
panying drawing, forming part thereof.

The figure is a perspective view of a solid fuel
range showing my new design.

I claim:

The ornamental design for a solid fuel range,
substantially as shown.

GEORGE E. PICKUP.
